UNITED STATES PATENT OFFICE.

JOHN JOHNSTON, OF WOONSOCKET, RHODE ISLAND.

DESIGN FOR A LOOM-SHUTTLE SPRING.

SPECIFICATION forming part of Design No. 33,954, dated January 22, 1901.

Application filed December 28, 1900. Serial No. 41,425. Term of patent 14 years.

To all whom it may concern:

Be it known that I, JOHN JOHNSTON, a citizen of the United States, residing at Woonsocket, in the county of Providence and State of Rhode Island, have invented and produced a new and original Design for a Loom-Shuttle Spring, of which the following is a specification, reference being had to the accompanying drawings, forming part thereof.

Figure 1 is a perspective view of a spring used in loom-shuttles and usually secured by a screw in the upper surface of one end of a loom-shuttle to bear on the heel of and control the position of the spindle. Fig. 2 is a longitudinal section of the spring.

As shown in the drawings, the leading and material feature of my design consists in the curved spring-plate of equal width and hav-

ing semicircular ends, from the concave side of which a boss projects, the ends of which unite with the plate by curved lines. A hole extends through the center of the boss, terminating on the convexly-curved side of the spring in an annular beveled shoulder.

Having thus described my invention, what I claim as new, and desire to secure by Letters Patent, is—

The design for a loom-shuttle spring as herein shown and described.

In testimony whereof I have signed my name to this specification in the presence of two subscribing witnesses.

JOHN JOHNSTON.

Witnesses:

J. A. MILLER, Jr.,
A. E. HAGERTY.
